(57) **CLAIM**

The ornamental design for a fishing lure, as shown and described.

DESCRIPTION

FIG. 1 is a front and left side perspective view of a fishing lure showing my new design;

FIG. 2 is a left side elevation view thereof showing a hook inserted into the fishing lure parallel to the plane of the tail; FIG. 3 is a top plan view thereof showing a hook inserted into the fishing lure perpendicular to the plane of the tail; FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawings are used to show environment of the fishing lure and form no part of the claimed design.
